UNITED STATES PATENT OFFICE.

ISAAC S. PURCELL, OF CHICAGO, ILLINOIS, ASSIGNOR TO TENTOBED COMPANY, OF CHICAGO, ILLINOIS, A CORPORATION OF ILLINOIS.

COLLAPSIBLE COT.

1,300,872.

Specification of Letters Patent. Patented Apr. 15, 1919.

Application filed June 4, 1917. Serial No. 172,597.

To all whom it may concern:

Be it known that I, ISAAC S. PURCELL, citizen of the United States, residing at Chicago, Illinois, have invented certain new and useful Improvements in Collapsible Cots; and I do hereby declare the following to be a full, clear, and exact description of the invention, such as will enable others skilled in the art to which it appertains to make and use the same.

My invention relates to beds or cots of the kind adapted to be compacted into a relatively small space, its general objects being to provide a structure of this class which will be strong and rigid when erected, in which the bed-bottom may readily be tightened or loosened, which may be quickly erected or disassembled, in which the number of tools for making the various parts will be reduced to a small number, which may readily be separated into a number of disconnected parts when disassembled, and in which certain of the parts may be used interchangeably in a number of different positions. Other and more detailed objects will appear from the following specification and from the accompanying drawings, in which drawings

Figure 1 is a plan view of the erected cot with the major portion of the bed-bottom fabric cut away.

Fig. 2 is a side elevation of the same.

Fig. 3 is an enlarged fragmentary end view of the same.

Fig. 4 is a fragmentary transverse section, taken along the line 4-4 of Fig. 3.

Fig. 5 is an enlarged fragmentary transverse section, taken along the line 5-5 of Fig. 1.

Fig. 6 is a perspective view of one of the punchings used for two different purposes as hereafter set forth.

Fig. 7 is a view of one of the side members of the cot when folded for shipment or storage.

Fig. 8 is a view of the same, partly unfolded.

Fig. 9 is a view showing the method of securing the punching of Fig. 6 when the same is to be used as a stop for certain parts of the cot frame.

Fig. 10 is a fragmentary perspective view of one end of the end rails and of a portion of the canvas or bed-bottom secured to the same.

To provide for compact storing and for a ready separation in case different portions of the cot are to be carried separately (as by boy scouts), I preferably construct the cot of my invention of seven separate portions, each self-contained but arranged for attachment to other cot parts without the use of screws or auxiliary fastenings of any kind. These seven parts are as follows:

Two side members, each comprising a foldable side rail, together with three legs and a foldable brace 10 for each leg, as shown folded in Fig. 7 and partially unfolded in Fig. 8.

A bed-bottom member, comprising a bed-bottom 1 of canvas or the like, end rails 2 and 3 secured to opposite ends of the bed-bottom, and sockets 4 at the ends of the rails 2 and 3 for engagement with the tips of the side rails.

Also, three spreader members, adapted interchangeably to be interposed between any one of the three pairs of laterally opposed legs, and each comprising a spreader bar 5 equipped at each end with hooks 6 for engaging pins 7 on adjacent cot legs, and a pair of braces 8 pivoted to the bar 5 and equipped with hook ends arranged for engaging pins 9 disposed higher on the cot legs than the pins 7.

Each of the folding braces 10 interposed between a cot leg 11 and one of the side rails 12 has a stop 13 for limiting a relative movement of the pivotally joined brace portions to a point just beyond an axial alinement of these portions, thus affording an effective stop after the manner long used with the braces for trunk lids and the like. Each side rail is preferably formed of two portions 12^A and 12^B connected by a pivot 14 disposed at a distance from the ends of both of these rail portions (as shown in Fig. 8) and one of these rail sections, and one of these sections carries a pair of stop lugs 15 both facing in the same direction. One of these lugs (15^A) is so positioned as to limit the unfolding movement of the rail sections

about their pivot, while the other (15^B) limits the folding movement to a position in which the rail sections align alongside each other. For each of these stop lugs I prefer-
 5 ably use a metal punching shown in perspective in Fig. 6, which punching is fastened to the wooden rail by a single bolt or rivet through the single perforation in the punching and is held from movement about this
 10 fastening as a pivot by the arm 16 of the punching, which arm enters a slot cut in the rail as shown in Fig. 9.

To reduce the weight of the cot and to prevent the discomfort of handling metal parts
 15 in either hot or chilly weather, I preferably construct the frame primarily of wood. That is to say, I use well seasoned wood for the side rails, legs and end rails, but preferably reinforce the latter by means of angle steel
 20 bars extending for their entire length and stiffening the end rails against the strains imposed on them by the tensioning of the bed-bottom when the cot is in use. Each of the side rail sections 12^A and 12^B has a free
 25 end 17 projecting beyond the pivotal connection of the rail section to one of the legs 11, thereby affording a projecting tip adapted to enter a metal socket 4 upon the adjacent end of one of the end rails, this socket being
 30 desirably integral with the angle steel reinforcement of the end rail and desirably constructed after the manner shown in my co-pending application filed Dec. 8, 1916, as Serial No. 135789. With the end rails de-
 35 tachably secured to the side rails by the socket and end lug arrangement thus described, the cot frame can readily be erected as a firm structure before the end rails and the bed-bottom carried by the latter (which
 40 bottom is here shown as a single piece of canvas) is attached to the frame. Then these end rails can readily be attached by first interengaging the socket tips of one of these rails with the projecting side rail tips at one
 45 end of the frame, then raising the side rail sections at the other end of the frame to shorten the distance between the opposite side rail tips and engaging the socket tips of the other end rail with the rail tips at the
 50 other end of the frame. Before making this last named connection, the free end rail may be rotated one or more half turns to tighten or loosen the bed-bottom, so as to provide the desired amount of tautness or of sag in the
 55 latter.

To simplify the erecting and manufacture, I preferably construct the pivotal joints 14 so that the rail sections 12^B will diverge slightly when unfolded (as shown in Fig. 1), thereby enabling me to use identical spreaders at each end of the cot frame. I also preferably construct the pivotal attachment of the intermediate legs 11 to the rail sections 12^A in such a manner that these legs will di-

verge slightly, thereby also enabling me to 65 use the same length of spreader between these legs.

I claim as my invention:

1. In a cot, a side member including a pair of normally horizontal bars pivoted to each other intermediate of their ends, and stops associated with said bars for limiting the relative movement thereof to positions in each of which the bars align horizontally with each other; each of the said stops consisting of a metal member having a portion engaging one of the side member bars to prevent rotation upon the latter, and having another portion affording a ledge substantially in the plane of the lower edge of the said bar. 80

2. In a cot, a frame comprising a pair of equivalent side members each consisting of two pivotally interconnected bars, two legs carried by one bar and one leg carried by the other bar of each side member, end rails respectively joining the ends of the side members, braces detachably interposed respectively between the opposed pairs of legs, and means associated with the said pivotal connection of the bars and with the legs for permitting the braces to be used interchangeably between the laterally opposed legs of the frame. 90

3. In a cot frame, the combination with a pair of laterally opposed legs and a spreader 95 detachably secured to both legs, of a latch on each leg for maintaining the spreader in its said position, said latch comprising a metal member pivoted to the leg and equipped with a pair of ledges positioned respectively for 100 engaging the spreader and an edge of the said leg.

4. A combination latch and stop member for cot frames, comprising an integral metal member equipped near one end for pivotal 105 mounting and at its other end with a forwardly projecting ledge, and equipped at one side with a rearwardly projecting ledge, as and for the purpose described.

5. In a cot frame, the combination with a 110 pair of laterally opposed legs, of a spreader interposed therebetween, said legs and spreader equipped with relatively interengaging formations, braces pivoted to the spreader and respectively interengaged with 115 said legs, and latches movably mounted on the legs and engaging the spreader to prevent accidental detachment of both the spreader and the braces from the legs.

6. A cot including two side rail members 120 each equipped with legs and each having side rail tips projecting beyond the legs, a pair of end rails, and a bed-bottom stretched between the rails, the end rails having socket tip formations slidably engaging the said 125 projecting rail tips.

7. A cot constructed as per claim 6, in which the legs are pivoted to the side rail

members by pivot plates disposed to act as stops for the socket tip formations on the end rails.

8. In a cot frame, a side rail member, leg-
5 pivot plates fast upon said member but spaced from the tip of the latter, and an end rail equipped with means for engaging the

said tip of the side rail members, the pivot plates being disposed to afford stops for limiting the said engagement of the end rail 10 with the tip of the side rail member.

Signed at Chicago, May 31st, 1917.

ISAAC S. PURCELL.
